PANIC-BOLT.

1,143,776.

Specification of Letters Patent. Patented June 22, 1915.

Application filed March 4, 1914. Serial No. 822,424.

To all whom it may concern:

Be it known that I, ALBERT A. PAGE, a citizen of the United States, residing in East Haven, county of New Haven, and State of Connecticut, have invented certain new and useful Improvements in Panic-Bolts, of which the following is a full, clear, and exact description.

This invention relates to panic bolts or emergency bolt mechanism for the doors of schoolhouses, theaters, and similar buildings, and it refers more particularly to mechanism of this kind in which one or more bolts are employed.

15 In the particular form of my invention selected for illustration, there are two bolts adapted to be mounted on the stile of the door, one of them coöperating with a socket or keeper in the lintel, and the other with a 20 socket or keeper in the floor, and in the following description I shall refer to a plurality of such bolts, but it will be understood that in the broader aspects of the invention the number of bolts is immaterial.

25 The primary object of the invention is to provide improved means for locking the bolts in retracted position as they are released to open the door. This permits the 30 subsequent closing of the door by taking hold of the bolt operating lever, or other member, at the inside of the door, without causing the bolts to be projected before they are in position to shoot into their keepers. Moreover, my improved construction is such 35 as to reduce to a minimum the likelihood of an unauthorized person damaging the bolt mechanism by tampering with it when the door is open. The detent mechanism for locking the bolts in retracted position is self- 40 acting, and so constructed and arranged that the bolts can only be released by one familiar with the mechanism, having a proper key or tool for the purpose intended.

45 Another object of the invention is the general improvement in construction and operation of emergency bolt mechanism of the type wherein a plurality of bolts are actuated by a single actuating lever.

To these and other ends, the invention 50 consists in the novel features and combinations of parts to be hereinafter described and claimed.

In the accompanying drawings, Figure 1 55 is a fragmentary inside elevation of a door, equipped with panic bolt mechanism, em-

bodying my improvements; Fig. 2 is an enlarged front elevation of the bolt actuating mechanism, showing the actuating lever in its depressed position corresponding to the retracted position of the bolts; Fig. 3 is a 60 side elevation of the operating mechanism, showing the lever in its elevated position; Fig. 4 is a similar view, showing the lever in its depressed position; Fig. 5 is a rear elevation of the bolt retracting mechanism, 65 with the back plate of the case omitted, showing the bolts protracted; Fig. 6 is a similar view, with the bolts omitted, and with the parts in a position corresponding to the retracted positions of said bolts. Fig. 70 7 is a section on line 7—7 of Fig. 5; Fig. 8 is an enlarged section on line 8—8 of Fig. 3; and Fig. 9 is an enlarged section on line 9—9 of Fig. 4.

Referring to the drawings, and more particularly to Fig. 1, 10 is a door equipped near the free edge thereof with a bolt 11, adapted to enter a socket or keeper in the lintel 12, a bolt 13, adapted to enter a socket or keeper in the floor, and bolt actuating 75 mechanism 14, including an operating lever 15. The lever 15 projects outward from the door at about the angle shown in Fig. 3 when the bolts are protracted, and when a panic occurs one or more persons in pushing 80 against the lever 15 voluntarily or involuntarily will move the lever downward into the position shown in Figs. 2 and 4, and thereby retract the bolts so that the door is 85 free to be pushed outward.

Referring now to the details of the mechanism, the retracting mechanism 14 includes a rim case 16, adapted to be secured to the inside face of the door by means of screws, passing through the screw holes 17, and having a back plate 18 (Figs. 7—9) detachably secured in place by means well known in the art. Projecting forwardly from the front wall 16^a of the case 16, are parallel ears or lugs 19, and fitting between said lugs, and in an opening 160 between them in the front wall of the case, is the shank portion 15^a of the lever 15. This lever is pivoted to the case by means of a pivot pin 20, passing through registering perforations in the lugs 19 and shank 15^a. The outward, or free end, of the operating 100 lever 15 is enlarged laterally with respect to the shank 15^a to provide an operating head 15^b of appropriate shape.

110

The pivot 20 of the lever 15 is located intermediate of the ends of said lever, the latter being provided at a point within the case 16 with a rounded extremity 15^a. Moreover, that portion of the lever adjacent the pivot 20 is cut away at opposite sides to receive the links 21 and 22, by which the retracting mechanism is connected with the upper bolt 11 and lower bolt 13 respectively. The lower end of the upper link 21 projects forwardly out of the case 16, as shown in Figs. 2 and 7, for which purpose the front wall 16^a of the case is provided with a suitable opening 23, communicating with the opening 160 between the lugs 19. The shank 15^a of the lever 15 is cut away at the side, at the upper part thereof, as indicated at 24, to accommodate the lower extremity of the link 21, which is pivoted to the lever 15 by a pin 25 at a point on one side of the main pivot 20. Similarly, the link 22 is accommodated in a cut out portion 26 on the opposite lower side of the shank 15^a and said link is pivoted to the main operating lever by a pin 27 located oppositely with respect to the pin 25 in reference to the main pivot 20. Hence, as the lever 15 is moved downward from the position shown in Fig. 3 to that shown in Fig. 4, the links will be moved toward each other, thereby retracting the respective bolts. The bolts 11 and 23 are preferably of semi-cylindrical form, and slide in extensions 28 and 29 on the case 16, being connected with the respective links by means of pins 21^a, 22^a.

A spring 30 projecting forwardly from the back plate 18 is adapted to engage a notch 31 in the lever shank 15^a, whereby the lever 15 when once moved into the position shown in Fig. 7 will be held in that position without jarring loose. The pivot pin 27 connecting the lower link 22 with the operating lever, being located at the rear face of the front wall 16 of the case is adapted to act as a stop, for which purpose said pin is extended laterally to one side of the lever, as shown in Figs. 5, 6 and 8. When the bolts are extended, as shown in Fig. 5, the pin 27 abuts the front wall of the case, as shown, and thereby acts as a stop. When the bolts are withdrawn, the pin 27 is moved through an arc of a circle into contact with the front wall of the case at another point, as shown in Figs. 6 and 8. In this manner, one of the pivot members connecting the operating lever with one of the bolts acts to limit the movement of the operating lever in both directions.

The detent mechanism for holding the lever 15 in its depressed position, corresponding to the retracted position of the bolts, is associated with the shank 15^a of the lever, and confined for the most part between the lugs 19, between which said lever is pivoted. In the form shown, the part

15^a of the operating lever is provided with a transverse bore 32, in which operates a plunger 33. A spring 34 in the bore or socket 32 acts at one end on the plunger 33, guided in said bore or socket, and at the opposite end against the inner face of one of the lugs 19. The plunger 33 is provided with a pin or projection 35, as best shown in Fig. 9, which is adapted to slide in contact with the inner face of the other lug 19. When the operating lever is depressed, as shown in Fig. 4, the pin 35 of the plunger 33 comes into alignment with an opening 36 in the adjacent lug 19, and is forced outwardly into said opening by the spring 34, as shown in Fig. 9, whereby the lever 15 is firmly locked against movement. Hence, the operating lever is automatically locked in position when it is pressed downward to release the bolts and permit the opening of the door. When it is desired to close the door again, this may be effected by grasping the lever 15, which is usually the only projection on the inside of the door which would serve as a hand-hold, and in this operation said lever cannot be shifted in such a manner as to project the bolts while the door is closing. When the door is fully closed a suitable key, or other instrument, is inserted into the opening 36 in order to press the plunger or bolt 33 out of locking engagement with its coöperating lug 19, whereupon the lever may be again elevated in an obvious manner.

It will be seen from the foregoing that the locking mechanism associated with the operating lever is of very simple construction, that it is called into action automatically on the opening of the door, and that it prevents the bolts from being thrown outward during the closing of the door, and the resulting damage to the bolt mechanism. Tampering with the mechanism by unauthorized persons is reduced to a minimum, as the method of operation of the locking mechanism is not apparent to the casual observer, and furthermore, because a suitable key or tool is needed to release the operating lever from its locked position.

I have not attempted to describe the various modifications of the construction which may be adopted within the scope of the invention as defined in the claims. Obviously, I do not limit myself to any particular form of operating lever, and in some aspects of the invention it is not necessary that the locking bolt for the operating lever be carried by the lever itself, as distinguished from some other part of the mechanism.

What I claim is:

1. In panic bolt mechanism, the combination of a case, an operating lever having a part projecting into the case, a bolt, a link connected with the bolt, a pin connecting the link with the lever, and means coöperating

with said pin to arrest the movement of the lever; substantially as described.

2. In panic bolt mechanism the combination of a case, an operating lever having a part projecting into the case, a bolt, a link connected with the bolt, a pin connecting the link with the lever, and means coöperating with said pin to arrest the movement of the lever in both directions; substantially as described.

3. In panic bolt mechanism, the combination of a case, a lever pivoted thereto and having a part projecting into the case, a bolt, a link connected therewith, and a member connecting the link with the lever and coöperating with one of the case walls to limit the movement of the lever; substantially as described.

4. In panic bolt mechanism, the combination of a case, a lever pivoted thereto and having a part projecting into the case, a bolt, a link connected therewith, and a member connecting the link with the lever and coöperating with one of the case walls to limit the movement of the lever in both directions; substantially as described.

5. In panic bolt mechanism, the combination of a case having a pair of lugs, a lever pivoted between said lugs, a bolt adapted for operation by said lever, and locking mechanism carried by the lever associated with one of said lugs; substantially as described.

6. In panic bolt mechanism, the combination of a case having a pair of lugs, a lever pivoted between said lugs, a bolt operable

by said lever, and a spring pressed detent bolt carried by the lever between the lugs and adapted to engage an opening in one of said lugs; substantially as described.

7. In a panic bolt mechanism, the combination of a casing, a lever pivoted thereto, a bolt operable by said lever, a positive locking means carried by the lever for locking the same in position automatically when the bolt is released, said locking means being arranged within the confines of the casing, substantially as described.

8. In a panic bolt mechanism, the combination of a casing, a lever pivotally connected thereto having one end outside the casing and the other confined within the casing, a bolt operable by said lever, and a spring actuated locking means carried by the lever and confined within the casing adapted to lock said lever in position when the bolt is released.

9. In a panic bolt mechanism, the combination of a casing having a lug thereon, a lever pivotally connected to said lug, a bolt adapted for operation by said lever, and a key actuated locking mechanism carried by the lever having a locking member associated with said lug as and for the purpose specified.

In witness whereof, I have hereunto set my hand on the 28th day of February, 1914.

ALBERT A. PAGE.
